UNITED STATES PATENT OFFICE.

LYCURGUS E. AMBROSE, OF MENA, ARKANSAS.

OIL-BURNER.

1,113,281.

Specification of Letters Patent.

Patented Oct. 13, 1914.

Application filed November 3, 1913. Serial No. 798,936.

To all whom it may concern:

Be it known that I, LYCURGUS E. AMBROSE, a citizen of the United States, and a resident of the city of Mena, county of Polk, and State of Arkansas, have invented certain new and useful Improvements in Oil-Burners, of which the following is a specification.

My invention relates to oil burners and more specifically to that class thereof designed to be arranged inside a stove to burn a liquid hydro-carbon as the fuel by reducing it to a vapor or gaseous form and then mixing the fuel gas or vapor with air to form a combustible mixture.

The object of my invention is the production of a burner of the character mentioned, which will be of durable and economical construction and efficient in use.

Other objects will appear hereinafter.

The invention consists in the combinations and arrangements of parts hereinafter described and claimed.

The invention will be best understood by reference to the accompanying drawing forming a part of this specification, and in which,

Figure 1 is a perspective view of a burner embodying my invention, Fig. 2 is a vertical transverse section of the burner, and Fig. 3 is a detail fragmentary horizontal section illustrating the intersection of the fuel pipe with the mixing chamber of the burner.

The preferred form of construction comprises a vaporizing or generating chamber 1 which is substantially U-shaped in form, one end of said chamber being connected with a liquid fuel supply pipe 2 which, in use, communicates with any suitable source of fuel supply.

Arranged directly below the vaporizing chamber 1 is a mixing chamber 3 in the form of an elongated cylinder or pipe, the corresponding ends of the members 1 and 3 being connected together and held in spaced relation by a link or strap 4. The upper end of the link 4 is connected with the member 1 by means of a pipe 5 the outer end of which is provided with a removable screw cap 6 through which access may be gained to the interior of the chamber 1 to effect ready cleaning thereof. A similar screw cap 7 is provided at the corresponding end of chamber 3 whereby access may be readily gained to the latter to effect cleaning of the same. Leading from the opposite end of the chamber 1 is a fuel or vapor conveying pipe 8 the lower end of which intersects the corresponding end of the chamber 3 as clearly shown in Figs. 2 and 3, pipe 8 being of a diameter considerably less than that of the interior of said mixing chamber so that air passages 9 will be formed in said mixing chamber at either side of said pipe. Formed in the pipe 8 is an orifice 10 through which the fuel vapor is discharged from said pipe into said mixing chamber.

The end of the mixing chamber 3 beyond pipe 8 is open to the outside atmosphere being equipped with a manually adjustable regulating device 11 of any approved design, the arrangement being such that, in the operation of the burner air will be admitted through the device 11 for mixture with the vapor injected into said chamber through the orifice 10. The lower end of the pipe 8 is equipped with a removable screw cap 8' through which access may be gained to the interior of said pipe for cleaning the orifice 10 when desired. The upper side of the mixing chamber 3 is provided with a plurality of spaced transversely extending slots or openings 12 through which the combustible mixture supplied to said chamber, during the operation of the device 11, is discharged for combustion.

Arranged below the chamber 3 is an oil pan 13 rigidly secured in position by means of straps 14 which embrace said chamber as clearly illustrated. Provided in the pan 13 at either side of chamber 3 are elongated openings 15 extending parallel with said chamber through which in the operation of the burner air will be permitted to pass in order to supply additional oxygen to the gas escaping from openings 12 in order to afford complete combustion whereby a maximum utilization of the fuel is obtained. Surrounding the openings 15 and the periphery of said pan are upwardly extending flanges 16 which prevent overflowing of said pan when oil is supplied thereto as is the case in the initial lighting of the burner as set forth in the following.

In the operation of the burner, the oil is first allowed to pass through the chamber 1, pipe 8 and chamber 3 so as to overflow into the pan 13 where the same is lighted. The heat of this combustion will convert the oil in the chamber 3 into vapor which will escape through the openings 12 of said chamber. Vapor thus escaping will mix with the

air arising through openings 15 and the mixture will burn directly under the vaporizing chamber with the effect of vaporizing the oil therein. After this initial lighting 5 the oil fed to the chamber 1 from pipe 2 will become vaporized in its passage therethrough by reason of the heat below and so that when the fuel reaches the pipe 8 it will be in a vaporous or gaseous state, being 10 charged into the chamber 3 in this form to mix with the air supplied to said chamber through the regulator 11. The orifice 10 through which the fuel vapor or gas is injected into the chamber 3 from pipe 8 being 15 so positioned in the latter that the air is admitted at the back thereof, the air passing through spaces 9 at either side of said pipe, a thorough mixture of the air with the fuel 20 gas or vapor is insured with a corresponding high degree of efficiency of the burner. By reason of a perfect mixture which is thus insured, the possibility of the flame creeping back in the chamber 3 to the air inlet 25 openings, such as not infrequently occurs in burners of this character now in use, is obviated. In use the burner will be so arranged in the stove that the air regulator 11 will be positioned exteriorly so that adjustment of said regulator may be effected at 30 any time in order to secure a perfect combustible mixture.

While I have illustrated and described the preferred form of construction for carrying my invention into effect, this is capable of 35 variation and modification without departing from the spirit of the invention. I, therefore, do not wish to be limited to the precise details of construction set forth, but desire to avail myself of such variations and 40 modifications as come within the scope of the appended claims.

Having described my invention what I claim as new and desire to secure by Letters Patent is:

1. A burner of the class described comprising an oil pan; an elongated vaporizing chamber and an elongated mixing chamber arranged above said pan with said vaporizing chamber positioned above said mixing chamber; a fuel supply communicating with 45 said vaporizing chamber; and a pipe establishing communication between corresponding ends of said vaporizing and mixing chambers, said end of said mixing chamber having air inlet openings, said oil pan having openings therein positioned adjacent opposite sides of said mixing chamber, substantially as described.

2. A burner of the class described comprising an oil pan; an elongated vaporizing chamber and an elongated mixing chamber arranged above said pan with said vaporizing chamber positioned above said mixing chamber; a fuel supply communicating with 60 said vaporizing chamber; a pipe establishing communication between corresponding ends of said vaporizing and mixing chambers, said ends of said mixing chamber having air inlet openings, said oil pan having 65 openings therein positioned adjacent opposite sides of said mixing chamber; and upwardly extending flanges surrounding said openings and provided at the periphery of 70 said pan, substantially as described.

In testimony whereof I have signed my 75 name to this specification in the presence of two subscribing witnesses.

LYCURGUS E. AMBROSE.
